UNITED STATES PATENT OFFICE.

MOSES C. JOHNSON, OF HARTFORD, CONNECTICUT, ASSIGNOR TO THE HELIX GEAR COMPANY, OF SAME PLACE.

DESIGN FOR A GEARING-COVER FOR VEHICLE-FRAMES.

SPECIFICATION forming part of Design No. 31,323, dated August 1, 1899.

Application filed July 5, 1899. Serial No. 722,880. Term of patent 14 years.

To all whom it may concern:

Be it known that I, MOSES C. JOHNSON, a citizen of the United States, and a resident of Hartford, in the county of Hartford and State of Connecticut, have invented a new and original Design for a Gearing-Cover for Vehicle-Frames; and I do hereby declare the following, when taken in connection with the accompanying drawings, to be a full, clear, and exact description of the same, and said drawings constitute part of this specification, and represent, in—

Figure 1, a view in side elevation of the gearing-cover; Fig. 2, an end view or front elevation of the gearing-cover; and Fig. 3, an end view, in rear elevation, of the gearing-cover.

My invention relates to a design for covers for gearing, which as a whole is a special article of manufacture and is ultimately connected to or forms part of the frame or attached parts of a bicycle. The structure when so used includes a cover for the crank-shaft, for the connecting-shaft, and for the gearing at the crank-shaft hanger and at the rear end of the frame; and my said invention consists in the configuration of the structure as hereinafter described, and shown in the drawings.

The structure as a whole presents, when viewed in side elevation, an elongated central part or rod *a*, terminating at one end in the circular enlargement *b* and at the other in a circular enlargement *c*, the latter being somewhat smaller in diameter than the former. The circular parts have their centers in line with the center line of the part *a*, the side lines of which merge more or less gradually into the circular outline of the parts *b* and *c* at each end.

Above the portion of the structure above

described is a central portion *d*, terminating at opposite ends in cylindrical parts *e* *f*, the latter being arranged directly over and surmounting the parts *b* *c*, the walls of the parts *b* and *e* and *c* and *f* merging into each other. 45

When viewed in front elevation, as in Fig. 2, the cylindrical part *b* is divided into two parts, one smaller in diameter than the other, the part directly underlying the cylinder *e* being the narrower.

When the structure is viewed from the rear, as shown in Fig. 3, the part *c* presents an oblong outline merging into the circular outline of the cylindrical part *f*.

A characteristic feature of the design resides in the arrangement of the parts *b* *c* and *f* and *e* with respect to each other, so that the parts, as *b* *c*, when viewed from the side are bounded by a circle and are surmounted by the oblong outline of the cylindrical enlargement, and when viewed from either end the oblong outline of the part *b* or *c* appears to be surmounted by the cylindrical outline of the part *e* or *f*. 55

The essential feature of my design is the arrangement of the parts *d*, *e*, and *f* above and substantially outward from the parts *a* *b* *c*, the latter, *b* and *c*, presenting the circular outline and the upper the oblong outline at the extremities. 70

I claim—

The design for a gearing-cover for vehicle-frames substantially as shown and described.

In testimony whereof I have signed this specification in the presence of two subscribing witnesses.

MOSES C. JOHNSON.
